UNITED STATES PATENT OFFICE.

HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

CAPACITANCE-CONTROL DEVICE.

Application filed May 29, 1922. Serial No. 564,312.

This invention relates to capacitance control devices for electric circuits and more particularly to variable condensers.

While not limited thereto, the invention is particularly applicable to radio and similar apparatus.

An object of the invention is that of providing an improved capacitance varying device for the aforementioned and other service.

Another object is that of providing a variable condenser of materially increased capacitance range and minimized space requirements.

Another object is that of providing such a condenser adapted to provide exceedingly close and accurate capacitance regulation without necessitating fine or delicate adjustment of its operating parts.

Another object is that of providing such a device comprising few, simple, durable and readily constructed parts compactly and conveniently arranged and capable of ready assembly.

Other objects and advantages will herein-after appear.

In the accompanying drawing wherein is illustrated a preferred embodiment of the invention,

Figure 1 is a vertical sectional view thereof, certain portions, however, being shown in elevation; while,

Fig. 2 is also a vertical sectional view, substantially on line 2-2 of Fig. 1.

Referring to the drawing, the condenser illustrated comprises essentially a plurality of juxtaposed conductive elements insulated from one another and provided with connections alternately to opposite sides of the controlled circuit, said elements being relatively adjustable to bring different values of surface area thereof into capacity relation with one another.

In practice such elements as well as the insulating medium therebetween, are preferably curved, whereas at least one of said elements is flexible and preferably of some resiliency, thereby permitting different portions thereof to be brought progressively into proximity to the other element or elements, while preserving a bias or tendency of the elements to separate one from another unless positively held.

In the drawing a single pair, 5 and 6, of elements are arranged in co-operative or po-

tentially co-operative capacity relation to one another and are maintained permanently and positively insulated by means of a relatively thin dielectric 7 preferably solid in character. The element 5 having the dielectric 7 wrapped thereabout is curved cylindrically and mounted upon a drum 8 for axial rotation or oscillation. A terminal portion of the element 6 is permanently secured to a peripheral portion of such cylindrical structure. The remainder of said element 6 is so disposed and held that upon rotation of such cylinder in one direction said element 6 is caused to wrap thereabout to an extent determined by the extent of such turning, whereas reverse rotation of the cylinder serves to produce an opposite effect. Obviously the effective capacitance of the device for any given setting thereof is a function of the area of the adjacent surfaces of the two elements thus caused to approximate one another.

In practice the flexible element 6 may conveniently be carried by and wrapped about a second drum 9 supported in proximity to the drum 8, the relation being preferably such that as the drum 8 is rotated in either direction the drum 9 is constrained to rotate also but in the opposite direction.

In practice said drums 8 and 9 are preferably rotatably carried by individual shafts 10 and 11 which in turn are mounted within or upon a suitable U-shaped frame member 12. Said frame may in practice be screwed or otherwise secured to a panel 13 or other vertical or horizontal support. The shaft 10 is adapted to penetrate the frame 12 and also preferably the support 13 and may carry beyond the latter a suitable knob 14 or other operating device. A set screw 15 provides for clamping the shaft 10 within the drum 8 in angularly and axially adjustable relation.

The drum 8 may preferably comprise a section of fibre tubing or the like clamped between a pair of circumferentially flanged end caps 16, 17 the latter being mounted upon a hub 18 and permanently secured thereto by spinning, swaging or the like against suitably disposed shoulders of the latter, said hub being in turn mounted directly upon the shaft 10 and secured thereto as aforescribed.

The element 5 is wrapped or otherwise assembled about the drum 8 and secured thereto by cementing or otherwise, being

spaced and insulated from the end caps thereof by the material of said fibre annulus. The dielectric 7 is similarly wrapped or otherwise assembled about the cylindrical element 5 and similarly secured thereto, as by cementing.

A terminal portion of the flexible element 6 is likewise secured to the outer surface of said dielectric as by means of screws 19 penetrating the material of the annulus and suitably insulated from the surrounding element 5 substantially as illustrated.

The drum 9 may be constructed substantially similar to the drum 8 aforescribed but may be preferably reduced in size for reduction of space requirements. Also in this instance a pair of spaced hub sections 18^a and 18^b are provided and may be free to rotate upon a common shaft 11 which latter may comprise a fixed stud or pinion as shown. The opposite end of the flexible element 6 may be screwed directly to the insulating annulus of the drum 9.

As shown particularly in Fig. 1, the element 6 is preferably made considerably narrower axially than is the element 5, whereas the width of the dielectric 7 is at least substantially equal to that of the element 5, thereby providing against surface leakage from one conductive element to the other.

In practice the drum 9 is preferably biased as by spring 20 to rotate in a direction to wind the element 6 thereon, such bias, however, being normally counteracted by means of a resilient frictioning member 21 mounted upon the frame and bearing against the adjacent end cap 17 of drum 8, whereby the movable parts are adapted to remain stationary unless positively moved but upon unwrapping rotation of the drum 8 the spring 20 is adapted to act automatically for winding the unwrapped portion of the element 6 about the drum 9.

The elements 5 and 6 may be composed of thin sheet brass, phosphor bronze or other conductive material having the desired characteristics, whereas the dielectric 7 may comprise thin bakelite or other of the well known insulating substances or may even be composed of paper, preferably coated and impregnated with an insulating substance as for example paraffine.

While the condenser as aforescribed is capable of ready adjustment to provide relatively small capacitance variations, it is nevertheless in many instances desirable to provide for still more close capacitance adjustment and to such end a vernier adjustment condenser may be advantageously combined with the elements hereinbefore described.

Such vernier adjustment device may conveniently comprise an independently operable condenser, mounted within the frame 12 and corresponding in all or most essential

respects to the construction just described except for being of much reduced axial dimensions.

In practice the drum 8^a of such vernier adjustment condenser is preferably mounted upon an individual shaft 10^a which may preferably extend within and through the hollow shaft 10 and its operating knob 14, said shaft being provided with an individual operating knob 14^a or the like. 75

The vernier adjustment drum 9^a may be mounted directly upon the stud 11 but capable of rotation thereon independently of the main condenser drum 9. The structure of the individual parts of such vernier device may be in all essential respects similar to that of the corresponding elements of the main condenser except for the aforementioned reduction in axial extent of the vernier adjustment elements, whereby no further description of such latter elements is required. 80

The necessary circuit connections for the aforescribed parts may be conveniently effected substantially in the manner illustrated, that is to say the outer faces of the drum 8^a are provided respectively with pairs 22 and 23 of collector rings insulated from said drum and from one another. The collector rings of each of the aforescribed pairs are electrically connected with one another as by through bolts 24 whereas the pair of collector rings 23 are also electrically connected with the elements 5 and 5^a of the main and vernier adjustment condensers 100 and the collector rings 22 are similarly connected electrically with the elements 6 and 6^a of the condensers. In practice such connections to the designated elements of the main condenser may comprise resilient contact fingers 25 and 26 having parts to engage the respective collector rings. 105

Additionally the frame 12 is provided with terminal studs 27 and 28 penetrating the same but insulated therefrom said studs carrying within the frame resilient contactors 29 and 30 adapted to electrically engage the left hand collector rings 23 and 22 respectively, the foregoing elements providing suitable circuit terminals for the device. 115

Obviously where the vernier adjustment elements are not employed the right hand set of collector rings may be mounted directly upon and in insulated relation to the frame 12 and permanently electrically connected with the respective terminal studs 27 and 28, the flexible contactors 25 and 26 being then adapted to make circuit with said rings precisely as in the construction specifically described and illustrated. 120

Obviously the specific capacitance of the aforescribed condenser may be predetermined at will by preselection of the axial width of its conductive elements. Also it is 130

apparent that the rate of capacitance variation for given ranges of operation of the device may be varied by varying the width of one or both of the conductive elements 5 throughout different portions of the circumferential length thereof, whereby the curve representing the relation of capacitance change to turning angle may be caused to assume practically any desired shape. It is to be noted that with the conductive elements 10 of uniform width as illustrated the aforementioned curve will be substantially a straight line, indicative of the operative characteristics which are ordinarily to be 15 preferred.

The aforescribed device when employed in radio apparatus has been found to be practically free from so-called body capacity effects which are objectionably characteristic 20 of most types of variable condenser. Such amelioration of this objectionable feature is so pronounced that in practice it has been found possible to construct the supporting frame, operating shafts, etc., except the operating handles, of metal and to operate the device manually without giving rise to any such objectionable effects.

Without limitation to any particular theory to account for such marked improvement in operation, it is believed that the extremely close juxtapositioning of the co-operating conductive elements permits the intermediate charge to concentrate therebetween to an augmented degree and minimizes the extent to which said charge exists 35 in the surrounding media.

What I claim as new and desire to secure by Letters Patent is:

1. In a variable condenser, in combination, a pair of independently rotatable drums 40 each having a peripherally carried conductive sheet and a dielectric sheet surrounding said conductive sheet and held in intimate contact therewith, additional individual conductive sheets for each of said drums having 45 a terminal portion secured flatwise to said respective dielectric sheets, means for rotating said drums selectively to cause said last mentioned conductive sheets to wrap about 50 the other sheets on the respective drums to an extent determined by the angle through which the drums are turned, individual tensioning means for forcing said additional conductive sheets into intimate contact with 55 the respective dielectric sheets upon such rotation of the drums, slip rings carried by one drum and electrically connected respectively with the corresponding conductive sheets of both drums, and fixed terminal means for 60 said rings.

2. In a variable condenser, in combina-

tion, a rotatable drum having a peripherally carried conductive sheet, a dielectric sheet surrounding said conductive sheet and held in intimate contact therewith, a second conductive sheet having a terminal portion secured flatwise to said dielectric sheet, means for rotating said drum to cause said second conductive sheet to wrap about said other sheets to an extent determined by the angle 65 through which the drum is turned, a second drum, means for securing a terminal portion of said second conductive sheet thereto, means biasing said second drum to rotate for winding said second sheet thereon and means 70 to act upon said first mentioned drum for overcoming such bias.

3. In a variable condenser, in combination, a pair of independently rotatable drums 80 each having a peripherally carried conductive sheet and a dielectric sheet surrounding said conductive sheet and held in intimate contact therewith, additional individual conductive sheets for each of said drums having a terminal portion secured flatwise 85 to said respective dielectric sheets, means for rotating said drums selectively to cause said last mentioned conductive sheets to wrap about the other sheets on the respective drums to an extent determined 90 by the angle through which the drums are turned, individual tensioning means for forcing said additional conductive sheets into intimate contact with the respective dielectric sheets upon such rotation of the 95 drums and tending to rotate said drums in a reverse direction, and means frictionally engaging said drums to hold the same in their respective adjusted positions against the action of said tensioning means. 100

4. In a variable condenser, in combination, a pair of axially aligned independently rotatable drums of relatively large and relatively small axial dimensions respectively, each of said drums having a conductive sheet 105 permanently secured thereto peripherally and a dielectric sheet surrounding each conductive sheet and held in permanent contact therewith, additional conductive sheets for each of said drums having a terminal portion secured flatwise to the respective dielectric sheets, individual tensioning means for said additional conductive sheets tending to maintain the latter unwound from said drums, and means for frictionally holding either or both of said drums in different rotary positions, with said conductive sheets wound thereon, against the action of said tensioning means. 110

In witness whereof, I have hereunto subscribed my name.

HENRY J. WIEGAND.
